[57] CLAIM

The ornamental design for a lap top computer, as shown and described.

DESCRIPTION

FIG. 1 is a reduced perspective view of a lap top computer showing my new design in the opened position;

FIG. 2 is a rear elevational view thereof;

FIG. 3 is a front elevational view thereof;

FIG. 4 is a top plan view thereof;

FIG. 5 is a bottom plan view thereof;

FIG. 6 is a right side elevational view thereof;

FIG. 7 is a left side elevational view thereof;

FIG. 8 is a reduced perspective view thereof in the closed position;

FIG. 9 is a front elevational view thereof;

FIG. 10 is a rear elevational view thereof;

FIG. 11 is a top plan view thereof;

FIG. 12 is a bottom plan view thereof;

FIG. 13 is a right side elevational view thereof;

FIG. 14 is a left side elevational view thereof;

FIG. 15 is a right side elevational view thereof similar to FIG. 6 showing the display window lowered and in the opened position; and,

FIG. 16 is a left side elevational view thereof.
